UNITED STATES PATENT OFFICE.

JOHN BENNETT, JR., OF CHICAGO, ILLINOIS, ASSIGNOR, BY MESNE ASSIGNMENTS, TO ECONOMY SEAT COMPANY, OF CHICAGO, ILLINOIS, A CORPORATION OF ILLINOIS.

CHAIR.

1,264,259.

Specification of Letters Patent. Patented Apr. 30, 1918.

Application filed July 6, 1917. Serial No. 178,915.

To all whom it may concern:

Be it known that I, JOHN BENNETT, Jr., a citizen of the United States, residing at Chicago, in the county of Cook and State 5 of Illinois, have invented certain new and useful Improvements in Chairs, of which the following is a specification.

This invention relates to an improved chair being particularly concerned with a 10 form of connection between the seat and a cushion which is removably secured thereto.

It is a primary object of my invention that the cushion may be secured to the seat by means which are easily manipulated, inexpensive to produce, and secure in its 15 operation. To this end my invention consists of a novel combination and arrangement of parts to be presently described and claimed; and in order that the same may be better 20 understood reference will be made to the accompanying drawing forming part of the specification, wherein—

Figure 1 is an inverted plan view of a chair bottom showing the cushion operatively in place;

Fig. 2 is a longitudinal section taken on line 2—2 of Fig. 1;

Fig. 3 is an enlarged detail of a connection between the cushion and seat, somewhat different from that illustrated in Fig. 2; and

Fig. 4 is a plan view of the device shown in Fig. 3, the cushion being removed to expose the parts.

Referring specifically to the drawing, I 35 have shown a chair bottom 5 the seat of which is in the form of a frame having an opening 6 over which is mounted a cushion or pad 7 secured to a backing plate 8. The cushion may be upholstered in any approved 40 manner. On the under side of the chair seat or bottom 5 the opening 6 is spanned by a bar 9 of wood or other appropriate material, the ends of the bar resting against the bottom of the seat and being preferably round- 45 ed as at 10 to provide a smooth end finish.

Intermediate its ends the bar carries two threaded members 11 which, in Figs. 1 and 2, are shown as thumb-screws. These threaded members pass through the open portion 50 of the chair seat and also through apertures formed in the backing plate 8. On that side of the plate where the cushion is mounted, nuts 12 are positioned within which the ends of the threaded members 11 55 are engaged. Each nut is held in a fixed

position upon the plate by a staple 13 or other suitable device, it being intended that the range of action of the threaded members shall not be sufficient to displace the staples from the backing at any time. 60

By the fastening means heretofore described, the cushion 7 is detachably connected to the seat portion of the chair, its removal being effected by proper rotation of the threaded devices to cause their disengagement from the nuts 12, whereupon the cross bar 9 is disconnected from the backing plate of the cushion. The entire cushion may then be removed for such purposes as are desired, and thereafter be replaced in 70 position by a reversal of the operations described.

In Figs. 3 and 4 I have shown a modification of the fastening means for connecting the cushion to the chair seat. This consists 75 of a conical nut 14 provided with radially extending wings or lugs 15 adapted, when forced into a cylindrical aperture within the backing plate, to lie in substantially the position indicated in Fig. 3. It will be noted 80 that the wings are each embedded within the material forming the backing in such a way as to prevent rotation of the nut therewithin. To prevent the nut from moving longitudinally from its correct position, I 85 prefer to use headed elements 16, such as tacks, which may be secured to the backing plate with their laterally projecting heads overlying a portion of the upper face of the nut. By this means the nut is prevented 90 from moving out of the aperture under any conditions.

In the form of connection shown in Figs. 3 and 4, the nut is enabled to lie within the backing plate so as to present its upper surface substantially flush with that of the plate, thereby eliminating the presence of the projecting elements in proximity to the underside of the cushion. Arranged to co-operate with the nut is a threaded device 100 such as a bolt 17 whose head 18 lies upon the under side of the cross bar to hold the cushion securely upon the seat. 95

I claim:

1. The combination with a chair seat comprising an open frame, a plate mounted thereon and a cushion attached to the plate, of a bar extending across the opening in the frame, screw-threaded bolts passing through the bar and the plate, nuts for the 110

ends of the bolts in engagement with the upper side of the plate, and means connected to the plate for preventing movement of the nuts with respect thereto.

- 5 2. The combination with a chair seat comprising an open frame, a plate mounted thereon and a cushion attached to the plate, of a bar extending across the opening in the frame, screw-threaded bolts having operating heads passing through the bar and plate, and wing nuts secured to the plate and recessed therewithin, said nuts being adapted

to receive the ends of the bolts, substantially as described and for the purposes set forth.

3. The combination with a chair seat comprising an open frame, a plate mounted thereon and a cushion attached to the plate, of a bar extended across the opening of the frame, screw-threaded bolts passing through the bar and plate, and conical winged nuts 15 for the ends of the bolts secured to the plate and recessed therewithin, substantially as described.

JOHN BENNETT, JR.
